[57] CLAIM

The ornamental design for a storage kit for cargo load locks, as shown and described.

DESCRIPTION

FIG. 1 is a perspective view of a storage kit for cargo load locks showing my new design, it being understood that the broken lines are for illustrative purposes only and forms no part of the claimed design;

FIG. 2 is a perspective view of the first component thereof;

FIG. 3 is a perspective view of the second component thereof;

FIG. 4 is a front elevation view of the first component thereof;

FIG. 5 is a left side elevation view of the first component thereof;

FIG. 6 is a right side elevation view of the first component thereof;

FIG. 7 is a bottom plan view of the first component thereof;

FIG. 8 is a front elevation view of the second component thereof;

FIG. 9 is a right side elevation view of the second component thereof;

FIG. 10 is a left side elevation view of the second component thereof; and,

FIG. 11 is a bottom plan view of the second component thereof.
